FIXING DEVICE FOR SLIDING CLASP
FASTENERS

Karl Friedrich Nägele, Berlin-Neukölln, Germany

Application December 9, 1932, Serial No. 646,563
In Germany December 22, 1932

13 Claims. (Cl. 153—1)

This invention relates to a device for fixing sliding clasp elements on a supporting band and consists in that, after the fastener elements have been placed on the supporting band, two counter 5 rotating cams fix them thereon and at the same time move on the band with the comb-like supporting device. The feed of the fastener elements onto the band is effected by a known magazine which has on its lower end a separate holding 10 device, by means of which the elements are fed singly and without jamming, into the gaps in the band carrier.

The known pressing on devices are open to the objection that, owing to their length, they sag because they simultaneously fix a relatively large 15 number of elements and thus produce irregular fasteners. Further, these devices prevent a mechanical feeding of the fastener elements. However, devices are also known by means of which 20 the fastener elements are fixed by means of rollers.

The device according to the invention presents the advantage over the known devices, that the fixing of the fastener elements on the cloth band 25 is effected in several consecutive phases at a more or less rapid speed according to the speed of rotation chosen, so that the elements produce an absolutely regular fastener. At the same time as the fixing of the links on the supporting band 30 the band carrier is moved on, owing to the tangential speed of the cam operating pressing jaws, and a positive drive for the feed of the band carrier is avoided. Consequently the feed of the band ceases automatically in the event of any 35 defect during the placing of the fastener elements on the band.

An embodiment of the invention is illustrated by way of example in the accompanying drawing in which:—

40 Fig. 1 shows the cloth band with a fastener element loosely placed thereon.

Fig. 2 shows a comb-like holding device in the form of a toothed steel band with longitudinal stiffening.

45 Fig. 3 shows the fixing device with cams in a section taken on the plane of the cam shafts.

Fig. 4 is a top plan view of the fixing device with cam operating means.

Fig. 5 is a part vertical section through the fixing device with mechanical feeding mechanism for the elements.

Fig. 6 is a vertical section showing the fixing device with a slightly modified mechanical feeding mechanism for the fastener elements.

55 The cloth band *a*, on which the fastener ele-

ments *b* must be placed and fixed, is placed in known manner between a two-part band carrier *c* with comb-like teeth *d* and this carrier *c* is slipped into a guide in a base plate *h*. In this base plate *h* two cam shafts *f* are arranged which 5 are interconnected by two toothed wheels *i* and effect the counter rotation of the two cam shafts. The two cam shafts *f* engage in fixing jaws *e*, which cannot yield laterally owing to a slot guide.

The feed of the fastener elements to the cloth 10 band *a* is effected by a magazine *m* in which the elements are previously ordered. To ensure that the elements *b* arrive regularly between the teeth *d* of the band carrier *c*, a foot *t* is arranged in front of the lower magazine aperture, which foot 15 the elements *b* straddle like riders. The two arms of the fastener elements then engage between the teeth of the carrier *c* and are consequently shifted during the movement of the carrier. They thus slide along the foot *t* until they can be placed on 20 the cloth band at the end of this foot *t*. The arrangement of such a foot *t* presents the advantage that only a single fastener element can drop into each gap in the band carrier *c*, *d*, because the next following element bears against the 25 point of the teeth *d* until the element *b* can fall into the next gap owing to the feeding of the carrier *c*.

Fig. 6 shows a modified form of construction for feeding the elements *b* onto the cloth band *a*. 30 A locking pawl *q* is rotatably mounted on the magazine *m* and is provided with a pin *r* projecting into the interior of the magazine. This locking, automatically controlled by the engagement of the locking pawl *q* in the tooth gaps, and 35 guides *s* situated on the end of the carrier *c* prevent the elements *b* from passing out of the magazine during the intermittent feeding of the carrier *c* a distance of one tooth *d* each time, so that a fastening element *b* can drop into the tooth 40 gap in question.

The fixing device according to the invention operates in the following manner:—

The carrier *c* with the inserted cloth band *a* is slipped into the guide in the base plate *h* until its 45 front end is gripped between the two cam jaws *e*. During the rotation of the cam shafts *f* the carrier *c* is pushed forward owing to the tangential speed of the jaws *e*. The two slightly bevelled jaws now press the first fastener elements gently 50 onto the band and the further the carrier is shifted, the stronger the fastener elements *b* will be pressed onto the cloth band *a* (Fig. 4). The fixing or pressing on operation is thus carried out in stages.

A roller p runs over the cloth band a and presses the elements uniformly on to the cloth band so that the fastener elements are fixed in a perfect manner on the cloth band.

5. The feeding of the fastener elements in front of the cam jaws is effected by the above described known magazine with the novel arrangements for holding back and perfect introduction of the fastener elements into the tooth gaps.

10. The fixing device according to the invention presents the advantage that the fastener elements are placed and fixed absolutely regularly on the cloth band and that the machine can run with the cams rotating at any desired speed. The 15 feeding of the band carrier is, as already stated, uniformly effected by the tangential speed of the jaws e . It is evident that the speed of feed of the carrier c can be increased by, for example, allowing the shaft collars k to run directly against 20 the carriers c or by slipping rubber discs or the like over the shaft collars k so that they effect the feed of the carriers c .

The operation of the device as compared with the known devices consists merely in inserting 25 the fastener elements b into the magazine m and placing into the machine the cloth band inserted in the carriers c .

I claim:—

1. A device for fixing sliding clasp fastener elements on the supporting cloth band, comprising two counter revolving cams movable toward and from the elements to press the same onto the band and at the same time to feed this band.

2. A device as specified in claim 1, in which the 35 cams lie substantially perpendicularly to the axis of the cloth band.

3. A device as specified in claim 1, comprising in combination with the cams, a magazine arranged above said cams, a cloth band carrier 40 adapted to feed the cloth band between said cams, guides on said carrier adapted to open the discharge aperture of the magazine when the said carrier passes thereunder and to close said aperture when the carrier has passed same.

45. 4. A device as specified in claim 1, comprising in combination with the cams, a magazine situated above said cams, band carriers adapted to feed the cloth band between said cams and under said magazine, combs on said carriers provided 50 with teeth, and a supporting foot on the lower end of said magazine situated between said combs adapted to support the fastener elements like riders and to allow the elements to drop one at a time in the gaps in said combs, said elements 55 being shifted along said foot by the teeth of said combs.

5. A device as specified in claim 1, comprising in combination with the cams, a magazine situated above said cams, band carriers adapted to 60 feed the cloth between said cams and under said magazine, combs on said carriers provided with teeth, and a locking device on said magazine adapted to cooperate with the tooth gaps and teeth in said combs to control the delivery of the 65 fastener elements from said magazine.

6. A device as specified in claim 1, comprising in combination with the cams, a roller arranged between said cams and adapted to press gently against the end face of the fastener elements

loosely placed on the band and to press same lightly onto the band before they are fixed by said cams.

7. A device for fixing sliding clamp fastener elements on a supporting cloth band including a band carrier on which the band is fixed, a magazine arranged above the carrier to feed the fasteners to the band, and means carried by the magazine controlled by the carrier for feeding the fasteners singly onto the band.

8. A device for fixing sliding clamp fastener elements on a supporting cloth band including a band carrier on which the band is fixed, a magazine arranged above the carrier to feed the fasteners to the band, means carried by the magazine controlled by the carrier for feeding the fasteners singly onto the band, and cams cooperating with the fasteners following their application to the band for clamping the same in position.

9. A device for fixing sliding clamp fasteners on a supporting cloth band, comprising means for placing the fasteners on the band, and rocking means for operating on said fasteners to simultaneously clamp the fasteners on the band and advance the band and clamped fasteners in a predetermined direction.

10. A device for fixing sliding clamp fasteners on a supporting cloth band, comprising means for placing the fasteners on the band, and means moving alternately toward and from said fasteners, said latter means acting when moving toward the fasteners to contact the same to simultaneously clamp the fasteners on the band and advance the band and clamped fasteners in a predetermined direction, the clamping means increasing in pressure as the band and fasteners advance.

11. A means for clamping fasteners on a band, including elements arranged on opposite sides of the band and movable in a substantially elliptical path, the major axis of which is substantially parallel to the band, with said paths crossing the unclamped fasteners, whereby the elements during such travel clamp the fasteners on the band and advance the band and clamp fasteners.

12. A device for fixing sliding clamp fasteners on a supporting cloth band, comprising means for placing the fasteners on the band, eccentrically operating clamping means for the fasteners when on the band, said means acting to clamp the fasteners on the band in a step by step operation through a series of impulses, each corresponding to one revolution of the eccentrically operating clamping means, said clamping means serving to advance the band and clamp the fasteners in a predetermined direction.

13. A means for fixing sliding clamp fasteners on a band, comprising opposing eccentrically operating clamping elements, and means for compelling intermittent and progressive pressure of said elements on the fasteners for clamping the latter on the band, said means also compelling a band feeding movement during such progressive pressure and imparting to each fastener a clamping impulse corresponding to the proportion of the length of the clamping surfaces to the eccentricity of the clamping elements.
